UNITED STATES PATENT OFFICE

ASA THEODORE BLOCKER, OF CHICAGO, ILLINOIS, ASSIGNOR TO INTERSTATE IRON
AND STEEL COMPANY, OF CHICAGO, ILLINOIS, A CORPORATION OF ILLINOIS

BAR TWISTER FOR ROLLING MILLS

Application filed June 22, 1927. Serial No. 200,540.

My invention relates to new and useful improvements in guides for turning or twisting metal bars between successive roll-passes, and consists in the organizations and arrangements of parts hereinafter described and claimed.

The invention is illustrated in practical embodiment in the accompanying drawings in which, Fig. 1 is a diagrammatic view showing the twister intermediate two successive roll-passes; Fig. 2 is a longitudinal vertical sectional view of the parts of the twister of Fig. 1; Fig. 3 is a detail front view of the body of the twister; Fig. 4 is a similar view 13 of the guide-holder of the twister; Fig. 5 is a side view of the guide-block of the twister, and Figs. 6 and 7 are detail cross-sectional views of the guide-block taken respectively on the lines 6—6 and 7—7 in Fig. 5 looking 20 in the direction of the arrows.

In the drawings and the reference numerals 1 and 2 represent two sets or pairs of rolls mounted in suitable housings 3 to form successive passes to roll metal shapes; the 25 passes may be arranged in line or side by side, and may be formed to roll any metal shape of other than circular cross-section, the term bar being used herein for brevity to 30 means and include any and all metal shapes of such description. Intermediate the passes a twister is arranged which turns a bar a half turn between the passes; for example, a flat metal bar 4 coming from a corresponding pass 1 with its wider faces horizontal will 35 enter the twister in this position and will be given a half turn by the twister so as to pass therefrom on edge to the next appropriate pass 2 as shown in Fig. 1, or vice versa the strip may enter the twister on edge from 40 the pass 1 and be given a half turn to pass from it with its wider faces horizontal to the pass 2 when the passes are relatively so formed. In the form here shown, the twister comprises a cast metal upright body 5 having 45 lateral feet 6 by which it is bolted in position and a longitudinal cylindrical bore 7 which is of larger diameter at its front portion to form a forwardly-facing rear shoulder 8; the upper portion of the body is tapped as at 9 50 to receive a set-screw 10. A cylindrical guide-

holder 11 longer than the body 5 fits in the bore 7 and has an inwardly facing shoulder 12 intermediate its ends to abut against the shoulder 8 to take the rearwardly directed thrusts to which it is subjected, and two taps 55 13 and 14 are spaced ninety degrees apart around the circumference of the holder to alternately receive the inner end of the set-screw 10 so that the holder can be set in different circumferential positions in the body 60 5. The holder has a longitudinal bore 15 which is irregular and preferably rectangular in cross-section and is formed with a bell-mouth 16 at its outer end which is irregular and preferably octagonal in cross-section as 65 shown in Fig. 4. A guide-block 17 fits in the bore 15 of the holder, being of corresponding length and peripheral contour and having a bell-mouth 18, and its outer end is 70 of corresponding outside octagonal contour as 75 shown at 19 to form a spigot to fit into the bell-mouth 16 of the holder to hold the guide-block against endwise and circumferential displacement in the holder. The guide-block 75 has a longitudinal central passage 20 which is formed intermediate its ends with a twist or turn of ninety (90) degrees as at 21 so that the bar passing through it is rotated or given a half turn between its entrance into and 80 exit from the guide-block. The passage 20 is irregularly shaped in cross-section to correspond with the contour of the bar being treated, and is here shown as rectangular to 85 accommodate the particular flat-bar 4 illustrated.

By turning the holder 11 in the body 5 and locking it by the set-screw 10 engaging either the tap 13 or the tap 14 the guide-block can be rotated or turned to present the front or 90 receiving end of its passage 20 with its longest dimension either horizontal or vertical, so that the bar 4 may enter it either flatwise or on edge as the character of the leading roll-pass 1 may require; the bar in its travel 95 through the guide-tube will be turned by the twisted portion 21 of the passage 20 to discharge therefrom on edge or flatwise accordingly. By removing the guide-block 17 here shown another similarly shaped block having 100

a suitably twisted passage of different shape or dimensions may be substituted; when a change of blocks is made it is necessary only to withdraw one block from the holder and insert another therein, as the endwise slip-joint formed by their lengthwise disposed interlocking parts enables the change to be made without manipulating any separate retaining devices, and in any case the interlocking parts co-operate to automatically position the block to present the entry end of its twisted passage in the desired circumferential position in relation to the associated roll-pass, and to afford both lengthwise and radially opposed bearings to positively hold the block against longitudinal and circumferential displacements. Furthermore, the means employed to lock the holder in the body also defines the circumferential adjustment of the guide to present the entry end of its twisted passage in different circumferential positions corresponding with different roll-passes.

I claim:

1. A bar twister comprising a body, a guide-block mounted in the body and having a twisted passage, and interlocking slip-joint connections between said body and block constructed to interengage when the block is seated endwise in the body and hold the block against rotation and longitudinal displacement on the body.

2. A bar twister comprising a body, a guide-holder mounted in the body, a guide-block seated in the holder and having a twisted passage, and interlocking connections between said block and holder constructed to interengage when the block is seated endwise in the body and hold the block against rotation and longitudinal displacement in the holder.

3. A rolling-mill bar twister comprising a body having a longitudinal bore, a guide-holder rotatable in the bore and fixed therein against longitudinal displacement, means to lock the holder in different circumferential positions in the bore, and a guide-block seated in the holder and provided with a longitudinal twisted passage of irregular cross-sectional area.

4. A bar twister comprising a body having a longitudinal seat, a guide-holder rotatably mounted in the seat and having a bell-mouth of irregular cross-section, means to lock the holder in different positions of rotation in its seat, and a guide-block seated in the holder and having a twisted passage and formed at one end to interlock with said bell-mouth.

5. A bar twister comprising a body having a longitudinal seat, a guide-holder rotatable in the seat and having circumferentially spaced taps, a screw on the body arranged to engage the taps to lock the holder in different positions of rotation in said seat, a guide-block seated in said holder and having a twisted guide-passage, and interlocking con-

nnections between the front ends of said holder and block.

6. A bar twister comprising a body having a longitudinal bore, a screw on the body, a guide-holder rotatable in the bore and having a bell-mouth of irregular cross-section and taps arranged to alternately register with said screw when the holder is rotated a quarter turn in its seat, and a guide-block seated in the holder and having a right-angle twisted passage and a spigot-end interlocking with said bell-mouth.

In testimony whereof I affix my signature.
ASA THEO. BLOCKER.
